PITCHER

Philip R. Marsh, Euclid, Ohio

Application May 14, 1949, Serial No. 2,648

Term of patent 14 years

(Cl. D44—21)

To all whom it may concern:

Be it known that I, Philip R. Marsh, a citizen of the United States, residing at Euclid, county of Cuyahoga, and State of Ohio, have invented a new, original, and ornamental Design for a Pitcher, of which the following is a specification, reference being had to the accompanying drawing, forming a part thereof.

Fig. 1 is a side elevational view of a pitcher showing my new design;

Fig. 2 is a top plan view;

Fig. 3 is a horizontal sectional view taken on line 3—3 of Fig. 1; and

Fig. 4 is a vertical fragmentary sectional view thereof taken on line 4—4 of Fig. 2.

I claim:

The ornamental design for a pitcher, as shown.

PHILIP R. MARSH.
